UNITED STATES PATENT OFFICE.

WEBSTER C. ESTES, OF BROOKLYN, NEW YORK.

DESIGN FOR A WOODEN BOTTLE.

SPECIFICATION forming part of Design No. 24,324, dated May 21, 1895.

Application filed April 20, 1895. Serial No. 546,562. Term of patent 14 years.

To all whom it may concern:

Be it known that I, WEBSTER C. ESTES, a citizen of the United States, residing at Brooklyn, in the county of Kings and State of New York, have invented and produced a new and original Design for a Wooden Bottle, of which the following is a specification.

In the drawings, Figure 1 represents my design by an elevation. Fig. 2 is a vertical section of the same, and Fig. 3 is a plan view.

The general configuration of the bottle is round and the leading features of my design consist in the pairs of curved bands with an intermediate plain body portion and the curved rib at the upper portion of the tapering neck portion.

The design of the body of the bottle comprises the plain parallel sided portions *a b*,

the double curved bands *c c'* near the bottom of the bottle and between the plain portions *a b*, the double curved bands *d d'* at the upper end of the portion *a*, the plain curved, tapering neck portion *e* extending from the bands *d d'* to the upper end of the bottle and the curved rib *f*.

The stopper has plain tapering sides *h h* and the convex top *i*.

What I claim is—

The design for a wooden bottle, substantially as shown and described.

Signed by me this 16th day of April, A. D. 1895.

WEBSTER C. ESTES.
